(57) **CLAIM**

The ornamental design for a vertical garden kit container, as shown and described.

DESCRIPTION

FIG. 1 is a top, front, left, perspective view of a vertical garden kit container showing our new design;

FIG. 2 is a bottom, left, rear, perspective view thereof;

FIG. 3 is a rear side elevation view thereof;

FIG. 4 is a left side elevation view thereof;

FIG. 5 is a front elevation view thereof;

FIG. 6 is a right side elevation view thereof;

FIG. 7 is a top plan view thereof; and,

FIG. 8 is a bottom plan view thereof.

The broken line showing is for the purpose of illustrating portions of the vertical garden kit container and forms no part of the claimed design.

1 Claim, 7 Drawing Sheets
